T. JELLOW

LETTER

Filed August 13, 1925

Fig. 1

*Inventor
Timothy Jellow*

by Jas. H. Linnell
his wife.

UNITED STATES PATENT OFFICE.

TIMOTHY JELLOW, OF QUINCY, MASSACHUSETTS, ASSIGNOR OF ONE-HALF TO GEORGE DI BOND, OF QUINCY, MASSACHUSETTS.

LETTER.

Application filed August 13, 1925. Serial No. 49,997.

This invention relates to a novel construction of an element or member of a design, inscription or the like, which is to be produced upon stones and particularly upon 5 monumental stones.

The design element is provided with a base member having formed therein or thereon a portion of the completed design, and said base member is preferably angular in shape 10 and provided on one or more of its sides or edges with notches or steps arranged in predetermined order to enable a plurality of base members to be properly assembled to complete the design, as will be described.

To enable the invention to be readily understood, the completed design is herein shown as a word, each letter of which constitutes an element of the design, and is composed of a base member, preferably a 20 substantially rectangular block or plate having the letter formed thereon and provided on two of its opposing sides or edges with a plurality of notches or steps of predetermined construction.

The notches or steps are arranged and made in such shape, size and number as to obtain combinations when the members are assembled together, so as to obtain the proper or desired spacing and preferably a substantially uniform spacing of the letters in the 30 word or design, notwithstanding that the base members of different letters may vary in size or width.

Letters embodying this invention are capable of being assembled to advantage in an apparatus or frame from which a transfer of the word or design in color is made on paper, which is then adhesively affixed to the stone or monument upon which the 40 design or word is to be cut.

The invention is particularly useful when the inscription is made of Roman letters which vary in width but which can be substantially uniformly or evenly spaced by 45 using blocks or plates having steps or notches of the proper depth.

To facilitate description, the design element will be hereinafter designated a letter.

The particular features of the invention 50 will be pointed out in the claims at the end of this specification.

Fig. 1 represents a frame in which are assembled a plurality of letters embodying this invention to form a word;

Fig. 2, a view like Fig. 1 with a transfer

sheet or layer of paper applied to the frame, showing the letters transferred in color thereto;

Fig. 3, a detail of a portion of the frame with letters assembled thereon to form a 60 different word;

Fig. 4, a plan of one of the letters on an enlarged scale, and

Fig. 5, a perspective of the letter shown in Fig. 4.

Referring to Fig. 4, *a* represents the base member of the improved letter, which base member may be made of metal, rubber or other suitable material of sufficient rigidity to permit its side edges to be provided with 70 notches or steps *b*.

The base member *a* has formed therein or thereon a letter, which as shown in Fig. 4 is an outline letter, formed by raised walls 10 attached to the base, but said letter may 75 be otherwise formed thereon or therein, as, for instance, it may be cut in the base member similar to a stencil.

The base member *a* is herein shown as provided with continuous and parallel top and bottom edges 12, 13, and with side edges 14, 15, which are of irregular form or outline, and composed of a plurality of sections or lengths which co-operate to form a plurality of notches or steps *b*.

In Fig. 4, the base member *a* has its side edge 14 provided with four lengths or sections numbered 16, 17, 18, 19, three of which are arranged in parallel planes and two in the same plane.

The sections 16, 18 are arranged in the same plane and the sections 17 and 19 in different planes. The section 17 is shown as the longest and lies between the sections 16, 18, which are shown as of substantially the 95 same length, while the section 19 is shorter than the section 18.

The sections 16, 18 co-operate with the section 17 to form two steps or notches *b* and the section 19 co-operates with the section 18 to form another step or notch *b*.

The side 15 of the base member *a* is provided as shown in Fig. 4 with five sections or lengths numbered 20, 21, 22, 23, 24, with the sections 20, 21 arranged in parallel planes; with the sections 20, 24 in the same plane; sections 21, 23 in another plane, and with the section 22 in a third plane.

The sections 20, 24 are shown as of the same length; the sections 21, 23 of unequal 110

lengths and of different length from the sections 20, 24, and the section 22 of greater length than any section on opposite sides thereof. The sections 16, 20 and 19, 24 are shown as of the same length, the sections 18, 23 of the same length and the sections 17, 21, 22 of different lengths. The base members *a* of the other letters of the alphabet are provided with side edges having a plurality of sections which form steps or notches *b*, and these steps or notches are arranged in suitable or predetermined order, so as to have one or more of the steps or notches match or fit one or more of the notches or steps of other letters, so that base members having letters of different widths may be assembled together to form an inscription or word and have the letters in the word spaced in a substantially uniform manner.

In Fig. 1 five letters forming the word or name DEWEY are shown as assembled on a frame comprising the parallel members 30, 31, and the cross members 32 which are attached to the member 30 and support the member 31, which latter is capable of being adjusted toward the member 30 and secured in its adjusted position by nuts 34 on bolts 35 movable in slots 36 in the cross members 32.

By reference to Fig. 1 it will be observed that each of the letters D, W is substantially wider than each of the letters E, Y, but by means of the steps or notches *b* in the base members *a* of these letters, the base members may be assembled with certain or predetermined sections of the base members registering with like sections on adjacent base members, so that the letters proper on the base members are spaced apart uniformly or substantially so, notwithstanding variations in the width of said base members.

In the cases of the word DEWEY, it will be seen that only the center sections on the adjacent edges of the letters D, E, register, whereas the three uppermost sections on the sides 15, 14 of the letters E, W register, and the two uppermost sections on the sides 15, 14 of the letters W, E register, and the three uppermost sections of the sides 15, 14 of the letters E, Y register.

In Fig. 3, the word YALE is shown, and the letters Y and E are the same as shown in Fig. 1, while the letters A and L are provided with a different construction or arrangement of steps or notches *b* in the sides of their base members.

The side 14 of the base member *a* of the letter A is provided with four sections or lengths, marked 30, 31, 32, 33, which are in

four different planes, the uppermost section 30 and the lowermost section 33 co-operating with the uppermost and lowermost sections of the side 15 of the letter Y, and the long section 31 co-operates with the second section of the letter Y, whereas the long section 32 and the next section 33 do not contact with the sections 40, 41 of the letter Y.

The side 15 of the letter A is provided with four sections 35, 36, 37, 38, with only the long section 37 and the short bottom section 38 contacting with sections of the letter L, which latter letter is provided on its side 14 with four sections, and on its side 15 with four sections, some of which differ in length from the sections in the side 14.

One embodiment of the invention is herein shown but it is not desired to limit the invention to the particular embodiment shown.

What is claimed is:—

1. An element capable of forming part of a design and comprising a base member provided with a component part of the design and having edges provided with steps some of which are of varying sizes according to the characteristics of the component part of the design, to obtain the proper spacing of the component parts when said base members are assembled to form the design.

2. A design element comprising a base member provided with a letter and having its side edges provided with steps, some of which are of varying sizes according to the characteristics of the letter on the base member, to obtain the proper spacing of the letters when said base members are assembled.

3. A design element comprising a base member provided with a letter and with top and bottom straight edges and side edges provided with sections forming steps, some of which latter vary in length according to the characteristics of the letter on the base member, to obtain the proper spacing of the letters when said base members are assembled.

4. A design element comprising a base member provided with a character and with parallel top and bottom edges and with side edges having sections in parallel planes and some of which vary in length to form steps of varying sizes according to the characteristics of the letter on the base member, to obtain the proper spacing of the letters when said base members are assembled.

In testimony whereof, I have signed my name to this specification.

TIMOTHY JELLOW.
